Primary Examiner — Caron D Veynar*Assistant Examiner* — Abraham Bahta(74) *Attorney, Agent, or Firm* — Michael E. Zall**(57) CLAIM**

I claim the ornamental design for a laser printable sheet for cards and badges, as shown and described.

DESCRIPTION

FIG. 1 is a front perspective view of the laser printable sheet for cards and badges showing my new design;

FIG. 2 is a front view thereof, the rear being identical thereto.

FIG. 3 is a right side view thereof, the left side view being identical thereto.

FIG. 4 is a top view thereof; and,

FIG. 5 is a bottom view thereof.

The broken lines in the figures depict environmental subject matter only and forms no part of the claimed design.
